Primary Examiner — Janice Hallmark*Assistant Examiner* — Adedoyin Taiwo Odeyale(74) *Attorney, Agent, or Firm* — Jose Cherson Weissbrot(57) **CLAIM**

The ornamental design for a handheld mist fan as shown and described.

DESCRIPTION

FIG. 1 is a front perspective view of a handheld mist fan, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right side view thereof;

FIG. 7 is a top plan view thereof;

FIG. 8 is a bottom plan view thereof;

FIG. 9 is a front perspective view of the handheld mist fan in an opened state; and,

FIG. 10 is another front perspective view of the handheld mist fan in another opened state.

The broken lines in the figures are for the purposes of illustrating portions of the handheld mist fan, which form no part of the claimed design.
